[57] CLAIM

The ornamental design for a tire, as shown and de-
scribed.

DESCRIPTION

FIG. 1 is a perspective view of a tire showing my new
design, it being understood that the tread pattern is
repeated uniformly throughout the circumference of
the tire, the opposite side being the same as that shown;
FIG. 2 is a side view of the tire in FIG. 1 on a reduced
scale;

FIG. 3 is a front view of the tire in FIG. 1;

FIG. 4 is an enlarged view of a tread portion of the tire
in FIG. 1; and,

FIG. 5 is a cross sectional view of the tire, taken ap-
proximately along line 5—5 in FIG. 2.
